(57) CLAIM

The ornamental design for a cookware handle, as shown and described.

DESCRIPTION

FIG. 1 is a perspective view of the “cookware handle”, showing my new design;

FIG. 2 is a top plan view thereof;

FIG. 3 is a front elevation thereof;

FIG. 4 is a bottom plan view thereof; and,

FIG. 5 is a right side elevational view thereof.

The broken line showings in FIGS. 1, 2, 4 and 5 are for illustrative purposes only, depicting the environment of the new design, forming no part thereof as claimed.
